(No Model.)

A. C. MCKENDREE.
LOGGING SLEIGH BOLSTER.

No. 371,273.

Patented Oct. 11, 1887.

UNITED STATES PATENT OFFICE.

ALBERT C. MCKENDREE, OF CONNEAUT, OHIO, ASSIGNOR OF ONE-HALF TO
JACOB WARFEL, OF ERIE, PENNSYLVANIA.

LOGGING-SLEIGH BOLSTER.

SPECIFICATION forming part of Letters Patent No. 371,273, dated October 11, 1887.

Application filed March 4, 1887. Serial No. 229,736. (No model.)

To all whom it may concern:

Be it known that I, ALBERT C. MCKENDREE, a citizen of the United States, residing at Conneaut, in the county of Ashtabula and State of Ohio, have invented certain new and useful Improvements in Logging-Sleigh Bolsters; and I do hereby declare the following to be a full, clear, and exact description of the invention, such as will enable others skilled in the art to 10 which it appertains to make and use the same, reference being had to the accompanying drawings, and to the letters of reference marked thereon, forming part of this specification.

My invention consists in the improvements 15 in logging-sleigh bolsters hereinafter set forth and explained in the specification and claims, and illustrated in the accompanying drawings, in which—

Figure 1 shows a logging-sleigh with my 20 improved bolster thereon in perspective. Fig. 2 shows a top or plan view of my improved bolster.

Like letters refer to like parts in both the figures.

In the construction of my improvement 25 shown the runners G and G' and the front cross-piece, H, are of usual and ordinary construction. The bolster, however, I construct of two pieces, A A', and the central piece, B. This central piece, B, is of about one-third of 30 the length of the pieces A A', and is secured between them by the bolts b b. The portion B of the bolster also projects somewhat above the side pieces, A A', so that the log will rest 35 upon it and not upon the pieces A A'. Some little distance from the ends of the central portion, B, I insert rods C C' through the side pieces, A A'. These rods C C' project out in front of the section A' of the bolster, so that 40 the log-chain can be looped around them to fasten it when desired. Near one end of the bolster I put in a shaft, I, having a claw, J, adapted to slip over and catch upon a chain 45 between the links thereof, by means whereof the chain can be wound around the shaft I to tighten it. This shaft I is provided on one end with a ratchet-wheel, E, upon which a small dog, e, operates to prevent the shaft I from turning back. In front of the ratchet- 50 wheel E, I place projecting pins F, between which a handspike can be inserted to turn the shaft I to wind a chain around it. If desired, I can place this device at each end of

the bolster; but in practice I find that the shaft and ratchet at one end of the bolster is 55 ordinarily sufficient for all practical purposes.

I secure this bolster, constructed as aforesaid, to the blocks D D' by means of bolts a, and I then secure the blocks D D' to the runners G and G' by means of bolts d, so that a 60 skid may be laid on the blocks D D' between the ends of the sides A A' of the bolster when necessary to roll a log upon the bolster.

In operation the log rests upon the central piece, B, of the bolster, and the chain is 65 fastened to one of the rods, C, and passed over the log and under the other rod, C, to the ratchet-shaft I, by means whereof it is drawn tightly around the log, holding it in place. If, however, the chain is used to draw the 70 sled or boat by, then the end, instead of being tightened by the ratchet-shaft I, is passed through the hole h in the front cross-piece, H, and the team hitched thereto, when the strain exerted by the team tends to tighten the chain 75 about the log and keep it tight while the log is being drawn on the sled or boat.

Having thus fully described my invention so as to enable others to construct and use the same, what I claim as new, and desire to secure by Letters Patent of the United States, is—

1. The combination, in a logging-sleigh bolster, of the side sections, A A', and the central section, B, with the rods C C', passing 85 through the side sections, A A', and projecting out in front of the section A', substantially as and for the purpose set forth.

2. The combination, in a logging-sleigh bolster, of the side sections, A A', the central 90 section, B, and the projecting rods C C', with the shaft I, provided with a catch or claw, J, and the ratchet E and dog e, substantially as and for the purpose set forth.

3. The combination, in a logging-sleigh bolster, of the side sections, A A', and the central section, B, with the supporting-blocks D D', substantially as and for the purpose set forth.

In testimony whereof I affix my signature in 100 presence of two witnesses.

ALBERT C. MCKENDREE.

Witnesses:

H. J. CURTZE,
JNO. W. SHANNON.
